VACUUM CLEANER

Nils Genell, Gothenburg, Sweden, assignor to
 Electrolux Corporation, Dover, Del., a corpora-
 tion of Delaware

Application July 8, 1936, Serial No. 89,565
 In Germany July 9, 1935

3 Claims. (Cl. 280—8)

The present invention relates to vacuum cleaners and more particularly to improved means for movably supporting a vacuum cleaner on a surface.

5 While not limited to vacuum cleaners of the following type, the invention is particularly well adapted for use in connection with cleaners having a dust separating member and motor-fan unit contained in a casing which is adapted to be connected to a suction nozzle by means of a flexible hose, the hose serving the dual purpose of conveying air from the nozzle to the casing and of pulling the casing around on the surface.

10 While it has been known to support such a vacuum cleaner unit by means of either runners or rollers, both of these means of support have certain advantages and both have certain disadvantages. When the unit is supported on a surface having a low degree of hardness such as a 15 soft rug, runners are preferable inasmuch as they distribute the weight over a comparatively large area and hence do not sink into the nap of the rug. Rollers, on the contrary, have but a small area of contact and hence concentrate the weight 20 of the unit to such an extent that the rollers sink into the rug and make it difficult to move the unit thereover. On a hard surface, on the other hand, rollers provide the better support inasmuch as they may roll easily thereover, while runners 25 produce a large amount of friction, may scratch the surface, and particularly if sand or the like is present on the surface, the movement of the runners thereover results in an objectionable grating noise. Also the runners become worn 30 excessively.

35 One of the objects of the present invention is to provide an arrangement whereby either runners or rollers may be employed at the option of the operator, depending usually on the type of surface on which the vacuum cleaner unit is supported.

40 Further objects and advantages of the invention will be apparent from the following description considered in connection with the accompanying drawing which forms a part of this specification, and of which:

45 Fig. 1 is a side view of a vacuum cleaner including one embodiment of my invention;

50 Fig. 2 is an end view of the device shown in Fig. 1;

55 Fig. 3 is a view similar to Fig. 2, but showing certain parts in a different position;

Fig. 4 is an end view of another embodiment of the invention;

55 Fig. 5 is an end view of a portion of the device

shown in Fig. 4, but with certain parts in different positions;

Fig. 6 is a cross-sectional view taken on the line 6—6 of Fig. 5; and

Fig. 7, 8 and 9 are cross-sectional views of three further embodiments of the invention.

Referring more particularly to Figs. 1 through 3 reference character 10 designates generally a vacuum cleaner unit including a preferably cylindrical casing 11 provided with reinforcing rings 10 12 and 13 at opposite ends thereof. A dust bag 13 and a motor-fan unit 14 are disposed within casing 11. An end member 15 provided with an exhaust opening 16 is secured to one end of casing 11, while an end member 17 is secured to the other end, as by spring clips 18. End member 17 is formed with a threaded central opening adapted to receive a coupling member 19 to which may be removably secured a flexible hose 20 leading to a suction nozzle 21. A rigid hollow handle member 22 may be interposed between hose 20 and nozzle 21.

Rings 12 and 13 are formed with pairs of lugs 25 and 26, respectively, disposed as shown in the drawing. Rotatably secured to lugs 25 in any 25 suitable manner are forked members 27 in which are rotatably mounted rollers 28. Forked members 29 are rigidly secured to lugs 26 and rotatably support rollers 30.

Lugs 25 and 26 are also formed with center 30 openings extending parallel to the axis of casing 11, which openings are adapted to rotatably receive the ends 31 and 32, respectively, of runners 33. These runners are shaped as shown in Fig. 1 so as to have a straight surface contacting portion 34 of a length substantially equal to that of cleaner unit 10. This straight portion is connected to the end portions 31 and 32 by curved portions 35 and 36, respectively. Portions 35 and 36 are so curved that the ends 31 and 32 are parallel to the long straight portion of the runners, and are also curved about a radius substantially equal to that of rings 12 and 13, as is shown in Fig. 3.

In operation, the motor-fan unit 14 causes air 45 to be drawn in through nozzle 21, handle 22 and hose 20 to within dust bag 13. Any dust entrained in the air is deposited within the dust bag, while the air passes through the material thereof to the fan and is discharged through the 50 exhaust opening 16. The unit 10 is normally placed on the floor behind the operator who grasps the handle 22 and moves the nozzle 21 back and forth over the floor. Due to the flexible connection provided by conduit 20 between the nozzle 55

and the unit 10, the unit is not moved back and forth with the nozzle, but as the operator works from one portion of the surface to another, the unit 10 is pulled along by means of the hose 20.

5 With the parts in the position shown in Figs. 1 and 2, the runners 33 support the unit on the surface, while the rollers 28 and 30 are spaced from the surface. Consequently, the entire weight of the unit is carried by the runners. This 10 is of advantage if the cleaner is supported on a soft yieldable surface such as a rug, inasmuch as the weight is distributed over a considerable area, thus tending to reduce penetration of the supporting means into the rug.

15 18 If, however, it is desired to support the cleaner unit on a hard surface, such as a hard wood floor, the runners 33 may be folded or pivoted up against the under-side of the casing 11, as is shown in Fig. 3. Due to the curvature of end portions 35 20 and 36, the runners conform to the outer contour of the casing. In this position of the runners, the rollers 28 and 30 contact the surface and support the entire weight of the unit. The pivotal connection between forked members 27 and lugs 25 25 provide a caster effect for the front rollers 28, thus permitting the unit to readily follow the hose.

Any desired means may be employed to retain the runners 33 in the different positions shown 30 in Figs. 2 and 3, respectively, and such an arrangement is shown in Fig. 6. As there shown, one of the lugs is provided with a wedge-shaped recess 40 having a curved wall into which recess extends a pin 41 rigidly connected to the runner. 35 The width of recess 40 limits the pivotal movement of the runners, and, due to the fact that the wall of the recess is curved, the pin 41 tends to remain at either end of the recess. The inherent resiliency of the runner permits the pin 40 to pass the high point at the middle of the curved wall.

In the embodiment shown in Figs. 4 through 6, the ends 31 and 32 of the runners extend completely through the lugs 25 and 26, respectively, 45 and forked members 27 and 29 are secured to these extended ends instead of being secured to the lugs. Consequently, the runners and the rollers on each side are pivotable as a unit. As shown in Fig. 4, the runners 33 are in contact 50 with the surface, while the rollers extend at an angle to the surface and are spaced therefrom. In the position shown in Fig. 5, the runners and rollers have been pivoted to a position in which the rollers contact the surface while the runners are spaced therefrom.

In the embodiment shown in Figs. 1 through 3, the center of gravity of the unit is at a different height from the floor when the rollers or runners, respectively, are used, while in the embodiment shown in Figs. 4 through 6 the height of the center of gravity remains substantially the same whether the rollers or the runners are in use.

In the embodiment shown in Fig. 7 the runners 65 33 are provided with vertical extending slots 45 near each end of the straight portion of the runners. A roller 46 is adapted to be rotatably supported in each slot by means of a supporting

member 47 formed with resilient arms 48 which are adapted to clamp around the runners.

The embodiment shown in Fig. 8 differs from that shown in Fig. 7 in that the runner 33 is solid while pairs of rollers 49 are rotatably secured to opposite ends of the supporting member 47 which resiliently clamps around the runner. 5

In the embodiment shown in Fig. 9, a supporting member 50 spans the runners 33 on opposite sides of the unit and rollers 51 are secured to opposite ends of the member 50 and outside the runners. 10

In each of the embodiments shown in Figs. 7, 8 and 9, the supporting members may be readily 15 snapped on and off the runners in order to attach and detach the rollers. When it is desired to use the cleaner unit on a surface having a low degree of hardness the rollers are removed whereby the unit is supported by the runners. 20 When it is desired to use the cleaner on a surface having a high degree of hardness the rollers are put in place, thus supporting the unit and spacing the runners slightly from the surface.

However, it is not necessary to remove the 25 rollers when it is desired to support the vacuum cleaner unit on a soft surface inasmuch as the rollers extend such a short distance below the runners that the latter carry most of the weight and limit the distance which the former penetrate 30 to such an extent that it is not objectionable.

While there has been shown several more or less specific embodiments of the invention, it is to be understood that this has been done for purpose of illustration only, and that the scope of the 35 invention is not to be limited thereby, but is to be determined by the appended claims viewed in the light of the prior art.

What I claim is:

1. In a vacuum cleaner including a casing 40 adapted to be moved over a surface, the combination with said casing of means for movably supporting the casing on the surface including runners and rollers fixed to each other and extending at an angle with respect to each other 45 and pivotally secured to the casing.

2. In a vacuum cleaner including a casing adapted to be moved over a surface, the combination with said casing of means for movably supporting the casing on the surface including 50 runners and rollers fixed to each other and extending at an angle with respect to each other and pivotally secured to the casing, and locking means for retaining the supporting means in a position with the runners in contact with the surface and selectively in a position with the rollers in contact with the surface.

3. In a vacuum cleaner including a casing adapted to be moved over a surface, the combination with said casing of an elongated runner 60 pivotally secured to each side of the casing, a roller rotatably secured to each end of each of said runners and angularly disposed with respect thereto, and means for retaining said runners in a position in contact with the surface and selectively in a position with said rollers in contact with the surface. 65

NILS GENELL.
